DOOR MACHINE

Charles V. McIntire, Short Hills, N. J., assignor to
Semet-Solvay Engineering Corporation, New
York, N. Y., a corporation of New York

Application August 2, 1940, Serial No. 349,805

11 Claims. (Cl. 212—4)

The present invention relates to door machinery, and particularly to an apparatus for operating "self-sealing" doors or horizontal coke ovens.

As used with horizontal coke ovens, "self-sealing" doors comprise a refractory plug projecting into the coking chamber and a metal sealing member at the outer side of the plug which is pressed into contact with the metal surface of the door frame of the chamber when the door is in place to seal the door opening. During the course of a coking period some of the volatile materials in the coal pass between the refractory plug and the walls of the coking chamber and form a cake or deposit on the relatively cool surface of the sealing member and door frame. Such deposits interfere with the reforming of a satisfactory seal between the sealing member and the door frame when the oven door is replaced after removal to permit pushing of the coke charge and it is now customary procedure to remove the deposits by scraping both sealing member and door frame manually each time the door is removed from the oven mouth.

Coke oven doors are removed to permit pushing and are replaced by door handling machines mounted for movement on tracks along the face of a coke oven battery. In the usual construction the tracks are so placed that there is very little clearance between the door machine and the buckstays of the coke oven. Due to the proximity of the door machine to the face of the battery it has been very awkward to clean the door, since the chassis of the door machine is in a position which interferes with the movement of the door away from the oven and which prevents turning the door to a position in which it can be cleaned more easily. In an attempt to escape this difficulty a complicated machine has been proposed which withdraws the door horizontally into a recess in the chassis, then raises it and slues it around horizontally ninety degrees to permit cleaning of the door.

It is an object of the present invention to provide a coke oven door machine of simple construction to remove the doors of coking chambers, bring them to a position above the base of the door machine in which they can be cleaned readily, and restore them to the mouth of the chamber.

It is a further object of the present invention to provide a coke oven door machine involving the use of a novel mounting for the door engaging member so that a door may be removed simultaneously upwardly and outwardly from the

mouth of a coking chamber, rotated to a position in which it can be cleaned readily, and then restored to the mouth of the chamber.

The door machine of my invention comprises a support fixed to a chassis or platform movable along a track on the coke bench of a coke oven battery parallel to the length of the battery, and a door carrier provided with a door engaging hook and supported for rotation about a vertical axis in vertically spaced swivel bearings carried by the support. The door carrier and bearings are so mounted that the bearings and carrier may be moved as a unit to bring the door engaging hook into engagement with a door at the mouth of a coking chamber, and then moved, with the door held by the hook, to a position above the platform. Thereafter the carrier may be rotated about its vertical axis to a position in which the door is readily accessible for cleaning.

10 To replace the door, the above operations are reversed.

In the accompanying drawings, forming a part of this specification and showing for purposes of exemplification a preferred apparatus in which the invention may be embodied and practiced but without limiting the claimed invention specifically to such illustrative instance,

Figure 1 is a vertical section of a coke oven door machine embodying the main features of the present invention, taken along the line I—I of Figure 2, showing the machine in position on the operating bench of a battery of horizontal coke ovens and in front of a self-sealing door which is in sealing contact with the door frame at the mouth of the coking chamber, the door lever and latch operating and releasing devices of the machine being shown in engagement with the oven door;

Figure 2 is a section taken along the line II—II of Figure 3;

Figure 3 is a section taken along the line III—III of Figure 2;

Figure 4 is a fragmentary horizontal section taken similarly to Figure 3 showing the mouth of the coking chamber, but showing the door swung from the mouth of the coking chamber to cleaning position;

Figure 5 is an enlarged showing of the mounting of the upper swivel bearing for the door engaging and supporting member;

Figures 6 and 7 are, respectively, horizontal and vertical enlarged sections showing the mounting of a latch tightening and releasing device; and

Figure 8 is a front view taken in the direction

of the arrows V, V, showing the door in position at the mouth of the coking chamber and showing the arrangement of the latch operating means of the door machine.

In Figure 1 there is shown in vertical section a door machine 1 positioned at one end of a horizontal coking chamber 2 forming one of a series of laterally adjacent chambers of a coke oven battery, a door frame 3 at the mouth of the chamber 2, and a "self-sealing" door 4 comprising a refractory plug 5 and a metal member 6 cooperating with the door frame 3 at the mouth of the chamber. The door 4 (see also Figure 8) is supported in sealing relation to the coking chamber by latch bars 7 rotatably mounted on the door 4 on spindles 8 which are formed with squared heads and with threaded portions 9 cooperating with threaded brackets 10 on the door so that the bars can be moved perpendicularly of the door by turning the spindles 8. Door frame 3 at the mouth of the coking chamber 2 is fitted with hooks 11 which are adapted to engage the latch bars 7 when they are rotated to the horizontal position. By turning the spindles 8 in one direction the latch bars 7 can be forced away from the door 4 and pressed against the hooks 11 to hold the door tightly against the door frame. By turning the spindles in the other direction the pressure is released and the latch bars 7 may be rotated out of engagement with the hooks 11 to permit removal of the door. The door 4 is provided with a hook 12 by which it is lifted by door machine 1 and with a boss 13 which cooperates with a bumper 13a on the door machine to hold the door erect during manipulation.

Door machine 1, shown in Figures 1, 2, 3 and 4, comprises a platform 14 mounted on flanged wheels 15 (turned by an electric motor, not shown) for movement on tracks 16 along the coke bench parallel to the face of the battery, and a framework 17 and pedestal 18 fixed to the platform 14. A door carrier 19 is mounted in vertically spaced crank arms 20 and 21 pivotally connected respectively to framework 17 and pedestal 18. The supporting framework 17 comprises uprights 22 and horizontal beams 23, 24, 25 and 26 at the top thereof. The framework is braced against distortion by suitable truss members 27 and 28. A rotatable shaft 29 to which are fixed crank arms 20 is supported in horizontal position parallel to the face of the battery by bearings 30 mounted on the horizontal beams 24, 25 and 26 of the framework. A swivel bearing 31 (shown in detail in Figure 5) is supported by trunnions 32 which are parallel to the shaft 29 and are journaled in bearings 33 at the lower ends of the arms 20. A second rotatable shaft 34, to which is fixed crank arm 21 having a length substantially equal to crank arms 20, is supported parallel to and beneath shaft 29 by bearings 35 on pedestal 18 which is fixed to the platform 14. Swivel bearing 36 is supported by a projecting shaft 37 which is parallel to shaft 34 and is journaled in bearing 38 in the lower end of arm 21. The shaft 37 is held against displacement from the bearing 38 by a washer and nut 39 secured to a threaded portion 40 of the shaft.

The door carrier 19 is provided at its lower end with a pintle 41 which is journaled in swivel bearing 36 supported at the end of arm 21, and at its upper end, with a pintle 42 which is journaled in swivel bearing 31 supported at the end of arm 20. As shown in Figure 5, pintle 42 is held against displacement from the bearing 31

by washer and nut 43 in threaded engagement with a threaded portion 44 of the pintle 42.

As shown in Figures 2 and 3, crank arm 45, fixed to shaft 29 and crank arm 46, of length equal to arm 45 and fixed to shaft 34, are connected at their ends by link 47. Link 47 is provided with a turnbuckle 47a and is adjusted to a length substantially equal to the distance between shafts 29 and 34. This crank arm and link connection between the shafts 29 and 34 insures that rotation of either arms 20 or arm 21 will cause arms 20 and 21 to rotate in unison, and the distance between the respective ends of the arms 20 and 21 will be maintained constant to hold the door carrier 19 firmly erect in vertical position. To effect rotation of the arms 20 and 21, a motor and speed-reducer assembly 48 is provided which operates a lever 49 which drives shaft 29 through link 50 and crank arm 45 on shaft 29. By operation of the motor in one direction the arms 20 and 21 can be moved to a downwardly pointing position (as shown in full lines in Figure 1) in which the door hook (hereinafter described) on carrier 19 will engage the door; and by operation of the motor in the other direction the arms can be swung to a substantially horizontal position (as shown in broken lines in Figure 1) pointing away from the coking chamber to move the door carrier 19 and door 4 above the platform 14. Spring mechanism 51 is provided in the link 50 to provide a cushioning effect to prevent injury to the machine or to the coke oven parts during operation.

Motor and speed-reducer assembly 52 mounted on lug 53 fixed to the swivel bearing 31 drives lever 54 which is connected through link 55 to a pin 56 fixed to and located eccentrically of the axis of door carrier 19. When the door carrier 19 has been swung to a position above the platform 14, as previously described, the motor 52 is operated and the door carrier 19 and door 4 are rotated ninety degrees about a vertical axis defined by the pintles 41 and 42 from the position shown in broken lines to the position shown in full lines in Figure 4 in which the door is readily accessible for cleaning.

Mounted on the carrier 19 and positioned to cooperate with spindles 8 on the door 4 when the carrier 19 is in the position shown in Figure 1, are two latch tightening and releasing devices 57 (see Figures 6 and 7), one for each of the top and bottom latches shown in Figure 8. Both devices are of the same design. Each of these devices comprises a motor and speed-reducer assembly 58 equipped with a torque-limiting control and connected to drive shaft 59 which is surrounded by a housing 60 and which extends through openings 61 in carrier 19. To the end of shaft 59 is fixed a wrench member 62 which cooperates with the squared ends of spindles 8 to rotate them to effect a loosening or tightening of the latch bars. As shown in Figures 6 and 7, the motor and speed-reducer assembly 58 is fitted with cross arms 63 and 64, of which oppositely disposed arms 63 are disposed in slots 65 of a bracket 66 on carrier 19 and the other two arms 64 of which are disposed with their ends bent to bear against the carrier 19. A spring 67, with one end against a projection 68 on the housing 60 of shaft 59 and with the other end against an inner wall of the carrier 19, presses the cross-arms against the base of the slots 65 and against carrier 19 respectively to hold the motor and shaft perpendicular to the carrier 19 until the wrench member 62 engages

the spindle and then permits a deflection of the wrench, shaft and motor to allow for possible misalignment of the spindle 8 and machine 1.

Referring to Figures 1 and 8, door hook lever 69 is pivotally mounted at 70 on the carrier 19 and is actuated through link connections 71 and cranks 72 driven by a motor and speed-reducer assembly 73, also mounted on the carrier 19. Attached to the door hook lever 69 and moved thereby is an arm 74, which is operatively connected to the link 75 by the opposed springs 76, to actuate the top and bottom latch operating members 77 through the lever 78, link 79 and connecting link 80 when the door hook lever 69 is operated to engage the door hook 12. As shown in Figures 6 and 8, each latch operating member 77 comprises an arm 81 pivoted on the housing 69 of the latch tightening and releasing device 57. The top and bottom latch operating members 77, as shown in Figure 8, are connected for rotation in unison by the connecting link 80. The arms 81 are provided with fingers 82 (Figure 6), one to engage and move each latch bar in a clock-wise direction and another to engage and move each latch bar in a counter-clockwise direction to rotate them to latched or unlatched positions when the latch operating members 77 are moved.

Operation of the machine is as follows: The machine with carrier 19 raised above the platform 14 is moved along track 16 to a position in front of the door 4 to be removed. Motor 48 is then operated to rotate the arms 20 and 21 downwardly to move the carrier 19 into the position shown in full lines in Figure 1. When the door carrier is in this position, wrench portions 62 of the latch tightening and releasing devices 57 are in operative engagement with the spindles 8 and the motors 58 are activated to turn the wrenches and spindles to release pressure on the latch bars 7. Motor 73 is then operated to move door lever 69 into contact with the door hook 12. Movement of the door lever 69 activates latch operating members 77 to rotate latch bars 7 to the unlatched position prior to contact between door lever 69 and the door hook 12. When connection between the door lever and the door hook is established and the door is firmly held on the carrier 19, motor 48 is operated to rotate the crank arms 20 and 21 about ninety degrees to swing the carrier 19 and door 4 to a position above the platform 14 of the machine. The motor 52 is then operated to move lever 54 and link 55 to rotate the door carrier 19 about a vertical axis to a position, which may be about ninety degrees from the original position, in which the door 4 and sealing member 6 are readily accessible for cleaning.

When the door is to be replaced, the above operations are reversed.

My apparatus has been found thoroughly satisfactory for the handling of coke oven doors to remove them from position at the mouth of a coking chamber to permit pushing of the coke and to bring them to a position where they are accessible for cleaning. The operation of the apparatus involves a minimum of sliding friction and is of simple and rugged construction.

It is to be understood that this invention is not restricted to the present disclosure otherwise than as defined by the appended claims.

I claim:

1. A door handling machine comprising in combination supporting means, a carrier rotatably mounted on the supporting means, door engaging means on the carrier, means for mov-

ing the supporting means and carrier in an arcuate path from a position in which the door engaging means engages a door in closing position, upwardly and outwardly away from said closing position, and means for rotating said carrier and door when moved into the upward and outward position.

2. A door handling machine comprising in combination a support, arms pivotally mounted on the support, for rotary movement about a horizontal axis, a door carrier mounted in said arms for rotary movement about a vertical axis, means to move the arms to move the carrier into position to engage a door and move the door upwardly and outwardly in an arcuate path, and means to rotate the carrier about a vertical axis.

3. Apparatus for removing a door from the mouth of a coking chamber which comprises a support, a pair of vertically spaced arms pivotally connected at their upper ends to the support, a door carrier pivotally connected to the lower ends of the arms, a door engaging hook on said carrier, means operable to rotate the arms to move the carrier into position so that the hook engages the door and also operable to rotate the arms to move the carrier upwardly and outwardly in an arcuate path from the mouth of the coking chamber, and means to rotate the carrier about a vertical axis.

4. Apparatus for removing a door from the mouth of a coking chamber which comprises a platform, a support fixed to the platform, a pair of vertically spaced arms pivotally connected at their upper ends to the support, a door carrier pivotally connected to the lower ends of the arms, a door engaging hook on said carrier, means to rotate the arms to move the carrier into position to have the hook engage a door at the mouth of a coking chamber and also operable to rotate the arms to move the carrier upwardly and outwardly in an arcuate path to a position above the platform, and means to rotate the carrier about a vertical axis.

5. Apparatus for removing a door from the mouth of a coking chamber which comprises a platform movable along the face of a battery of ovens, a support fixed to the platform, a pair of vertically spaced arms of equal length pivotally connected at their upper ends to the support, a door carrier pivotally connected to the lower ends of the arms, a door engaging hook on said carrier, means operable to rotate the arms in unison to move the carrier into position to have the hook engage a door at the mouth of a coking chamber, and to rotate the arms in a reverse direction to move the carrier away from the mouth of the coking chamber upwardly and outwardly in an arcuate path to a position above the platform, and means to rotate the carrier about a vertical axis.

6. Apparatus for removing a door from the mouth of a coking chamber which comprises a platform, a framework and a pedestal fixed to the platform, a pair of vertically spaced arms of equal length pivotally connected at their upper ends, one to the framework and the other to the pedestal, a door carrier pivotally connected to the lower ends of the arms, a door engaging hook on said carrier, means operable to rotate the crank arms in unison in one direction to move the carrier into position to have the hook engage the door at the mouth of the coking chamber, and to rotate the arms in a reverse direction to move the carrier away from

the mouth of the coking chamber upwardly and outwardly in an arcuate path to a position above the platform, and means to rotate the carrier about a vertical axis.

7. Apparatus for releasing and removing a door from the mouth of a coking chamber which comprises a platform mounted for movement parallel to the face of a battery of ovens, a framework and a pedestal fixed to the platform, a pair of vertically spaced crank arms of equal length pivotally connected, one to the framework and the other to the pedestal, for rotation about horizontal axes parallel to the face of the battery, bearings carried at the ends of the crank arms, a carrier supported in vertical position by the bearings and rotatable about a vertical axis, means mounted on the carrier to release the fastenings of a coke oven door, hook means also mounted on the carrier to engage and support the door, means to rotate the crank arms in unison to move the carrier towards the door at the mouth of the coking chamber to a position in which the means to release the fastenings engage the fastenings and the hook means engage the door, and also operable to rotate the arms to move the carrier and door upwardly and outwardly away from the mouth of the chamber to a position above the platform, and means to rotate the carrier and door about a vertical axis to a position in which the door is accessible for cleaning.

8. Apparatus for removing a coke oven door from the mouth of a coking chamber which comprises a support, vertically spaced arms pivotally connected at their upper ends to the support for rotation about horizontal axes which are parallel to the face of the coke oven, horizontal shafts parallel to the face of the oven journaled in the lower ends of the arms, vertical swivel bearings carried by the shafts, a door carrier mounted for rotation about a vertical axis in the swivel bearings, a door engaging hook on said carrier, means operable to rotate the arms to move the carrier into position so that the hook engages a door at the mouth of a coking chamber, and also operable to rotate the arms to move the carrier upwardly and outwardly in an arcuate path away from the coking chamber, and means supported by one of the horizontal shafts to rotate the carrier about a vertical axis.

9. Apparatus for removing a coke oven door from the mouth of a coking chamber which comprises a support, vertically spaced arms pivotally connected at their upper ends to the support for rotation about horizontal axes which are parallel to the face of the coke oven, horizontal shafts parallel to the face of the oven journaled in the lower ends of the arms, vertical swivel bearings carried by the shafts, a motor supported by one of the shafts and held thereby against rotation about a vertical axis, a door carrier mounted on

the swivel bearings for rotation about a vertical axis, a door engaging hook on said carrier, means operable to rotate the arms to move the carrier into position to have the hook engage the door at the mouth of the coking chamber, and also operable to rotate the arms to move the carrier upwardly and outwardly in an arcuate path away from the coking chamber, and link means operative between the motor and a point eccentric of the door carrier to rotate the carrier about a vertical axis.

10. Apparatus for removing a coke oven door from the mouth of a coking chamber which comprises a platform mounted for movement along the face of a battery of coke ovens, a support fixed to the platform, horizontal vertically spaced shafts rotatably mounted on the support, arms of equal length fixed at their upper ends to the shafts, vertical swivel bearings supported by trunnions journaled in the lower ends of the arms, a door carrier mounted for rotation about a vertical axis in the swivel bearings, a door engaging hook on said carrier, link means operable to rotate the horizontal shafts in unison to move the arms and swing the door carrier into position to have the hook engage the door at the mouth of the coking chamber and also to move the carrier upwardly and outwardly in an arcuate path away from the coking chamber, a motor fixed to the exterior of one of the vertical swivel bearings, a lever moved by said motor, and link means operative between the lever and a point eccentric of the door carrier to rotate the carrier about a vertical axis.

11. Coke oven apparatus comprising a series of coking chambers forming a coke oven battery, doors at the mouths of the coking chambers, a platform mounted for movement along the face of the battery, a support fixed to the platform, a pair of vertically spaced crank arms of equal length pivotally connected at their upper ends to the support for rotation about horizontal axes parallel to the face of the battery, a door carrier pivotally connected to the lower ends of the crank arms and rotatable about a vertical axis, a door engaging hook on said carrier, means on the carrier to release the fastenings of a coke oven door, link means operable to rotate the crank arms in unison to move the carrier into position in which the means to release the fastenings of the door engage the fastenings and the door engaging hook engages the door, and also operable to rotate the arms in the reverse direction to move the carrier and door upwardly and outwardly from the mouth of the chamber to a position above the platform, and means to rotate the door about a vertical axis to a position substantially ninety degrees from its position at the mouth of the chamber.
